DESIGN FOR A DRESS

Emily Wilkens, New York, N. Y.

Application December 5, 1945, Serial No. 124,376

Term of patent 3½ years

(Cl. D3—26)

To all whom it may concern:

Be it known that I, Emily Wilkens, a citizen of the United States of America, residing in New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

I claim:

The ornamental design for a dress, substantially as shown.

EMILY WILKENS.
